US00D777252S

(12) **United States Design Patent** (10) Patent No.: **US D777,252 S**
Nicklaus et al. (45) Date of Patent: ** *Jan. 24, 2017

(54) **INTERACTIVE ELECTRONIC CARD WITH BUTTONS**

(71) Applicant: **Dynamics Inc.**, Cheswick, PA (US)

(72) Inventors: **Eric R. Nicklaus**, Pittsburgh, PA (US);
Jeffrey D. Mullen, Pittsburgh, PA (US)

(73) Assignee: **DYNAMICS INC.**, Pittsburgh, PA (US)

(*) Notice: This patent is subject to a terminal disclaimer.

(**) Term: **14 Years**

(21) Appl. No.: **29/447,432**

(22) Filed: **Mar. 4, 2013**

(51) LOC (10) Cl. **19-08**

(57) **CLAIM**

The ornamental design for an interactive electronic card with buttons, as shown and described.

DESCRIPTION

FIG. 1 is a front, bottom, and left side perspective view of our new design for an interactive electronic card with buttons;

FIG. 2 is a front, top, and left side perspective view thereof;

FIG. 3 is a front side view thereof;

FIG. 4 is a back side view thereof;

FIG. 5 is a top side view thereof;

FIG. 6 is a bottom side view thereof;

FIG. 7 is a left side view thereof; and,

FIG. 8 is a right side view thereof.

The broken lines showing environment in the drawings are for illustrative purposes only and form no part of the claimed design.

1 Claim, 5 Drawing Sheets
